(57) **CLAIM**

The ornamental design for a transparent collector of breast pump, as shown and described.

DESCRIPTION

FIG. 1 is a perspective view of a transparent collector of breast pump, showing my new design according to an embodiment;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded view thereof.
